UNITED STATES PATENT OFFICE.

ISAAC W. ENGLAND, OF PASSAIC, NEW JERSEY, ASSIGNOR TO PASSAIC METAL WARE CO., OF PASSAIC, NEW JERSEY, A CORPORATION OF NEW JERSEY.

CONVEYER.

Application filed December 1, 1921. Serial No. 519,036.

To all whom it may concern:

Be it known that I, ISAAC W. ENGLAND, a citizen of the United States, and resident of Passaic, in the county of Passaic and State of New Jersey, have invented certain new and useful Improvements in Conveyers, of which the following is a specification.

This invention relates to improvements in conveyers, and has particular reference to 10 conveyers of the endless chain variety that are provided with means to support other parts on the links of the conveyer.

This invention is particularly adapted to support arms on the conveyer to retain 15 sheets or plates on edge while being moved through baking ovens, such as for baking lithographic ink on the plates.

The invention comprises novel details of improvement that will be more fully herein- 20 after set forth and then pointed out in the claims.

Reference is to be had to the accompanying drawings, forming part hereof, wherein—

25 Figure 1 is a side elevation illustrating my improvements in connection with a baking oven;

Fig. 2 is an enlarged detail plan view of a portion of the conveyer;

30 Fig. 3 is a cross section on line 3, 3, in Fig. 2; Fig. 4 is a detail perspective of one of the improved links of the conveyer;

Fig. 5 is an enlarged detail of part of one of the supports;

35 Fig. 6 is a cross section illustrating the conveyer having supports for metal plates or sheets;

Fig. 7 is a detail plan view of a modified form of the conveyer, and

40 Fig. 8 is a cross section of Fig. 7.

Similar numerals of reference indicate corresponding parts in the several views.

The conveyer is shown comprising endless chains 1 spaced apart, being carried upon 45 sprocket wheels 2, 3, 4, journaled upon brackets 5, 6, carried by the frame 7. The chains may be propelled in any suitable manner, such as by means of pulley 8 on shaft 9 receiving belt 10 from a suitable 50 source of power. The chains of the conveyer illustrated comprise links, pins and rollers, some of which links are provided with laterally disposed ears or lugs to retain supporting arms or bars for sheets or plates 11. In

the form shown in Figs. 2 and 3 the links 12 55 are connected together in the usual way, having holes near their ends receiving cross pins 13 that have holes near their ends receiving retaining pins 14, such as cotter-pins, rolls 15 on pins 13 being shown interposed between 60 corresponding links 12 to space them. Links 16 are provided at opposite ends with holes 17 to receive the spaced pins 13 of the conveyer chain, which links 16 on opposite edges between holes 17, are provided with laterally 65 extending ears or lugs 18, spaced apart. Said ears or lugs are shown provided with apertures 19 which oppose or register to receive supports 20. The holes 17 of links 16 receive the pins 13 and are retained on said 70 pins by the retaining pins 14. In the form illustrated in enlarged Figs. 2 and 3 supplemental links 16 are outside of the main links 12 on one side of a chain and the ends of adjacent links 16 overlap one another, by 75 preference ears 18 of one supplemental link 16 being longer than the ears 18 of adjacent or alternate links 16 on opposite sides thereof, so that the apertures 19 of the several sets of ears will be in alignment along the 80 side of the chain, the alternate supports 20 having corresponding width. In the form shown in Figs. 7 and 8 the links 12 on one side of the chain are dispensed with and the links 16 having the ears or lugs 18 constitute the links of such side of the chain, being supported upon the pins 13. While 85 Figs. 7 and 8 illustrate the simpler form of the two constructions described an advantage 90 in the form shown in Figs. 2, 3, and 6 is, that if supplemental links 16 are to be replaced the said links can be removed without disturbing the continuity of the chain, since the links 12 will remain attached to pins 13 of the chain, whereas, if links 16 in Figs. 7 and 8 are to be removed the adjacent pins 13 of the chain become released on the corresponding side of the chain.

The supports 20 are shown in the form of 100 wires having substantially straight parallel spaced arms 20^a, the wires or rods being bent into hook-like form at 20^b, connected together by the V-like portion 20^c extending between the arms 20^a and bracing the same laterally. The free ends of arms 20^a of each 105 support 20 are passed through the registering apertures 19 in the ears or lugs 18 of the corresponding link, and respectively on op-

posite sides of the said ears or lugs the arms 20^a are swaged to produce projections 21 to bear against said ears to retain the supports 20 on the latter and prevent longitudinal movement thereof. The corresponding ends of arms 20^a may be inserted through the registering apertures 19 of ears 18 of the conveyer and the projections 21 then may be swaged on said arms, which 10 projections may be bent back or removed in case it is desired to detach the supports 20 from the corresponding links. Supports 20 may be removed and replaced with links 16 remaining attached thereto by removing 15 said links from the conveyer chains.

In the example illustrated in Fig. 6, the conveyer comprises two endless chains, as described, spaced apart, with supports 20 having their ends attached to ears or lugs 18 of links 16 of said chains and located between the two chains which are to travel together, so that the supports 20 may project in spaced relation from the conveyer in position to receive sheets or plates 11 edgewise 25 upon the conveyer, to be retained in proper position to travel with the conveyer. The chains may glide upon rails 22, passing through the baking oven or chamber 23 of any suitable construction, which is open at 30 opposite ends for the travel of the conveyer to carry the plates edgewise therethrough.

An advantage of the improvement set forth is that the ears or lugs 18 are an integral or non-movable part of the links, so 35 that there will be no danger that the ears or lugs will have movement relative to the links, whereby the supports 20 will be retained in proper positions on the conveyer and will not be displaced as the conveyer 40 travels, by which means the plates or sheets 11 will be retained properly in spaced relation on the conveyer.

Having now described my invention, what I claim is:

1. A conveyer comprising spaced chains 45 having side links and connecting pins, supplemental links upon said pins adjacent to corresponding side links of the pins, and supports carried by and extending between opposing supplemental links of the spaced 50 chains.

2. A conveyer comprising spaced endless chains having side links and connecting pins, supplemental links upon said pins adjacent to corresponding side links of the pins, the supplemental links having laterally disposed spaced apertured ears, supports having arms located in the apertures of corresponding ears, and means to retain said arms upon said ears. 60

3. A conveyer comprising spaced endless chains having side links and connecting pins, supplemental links upon said pins adjacent to corresponding side-links of the pins, the supplemental links having laterally 65 disposed spaced apertured ears, the ends of alternate supplemental links overlapping, supports having arms located in the apertures of corresponding ears, and means to retain said arms upon said ears. 70

4. A conveyer chain comprising side links and connecting pins, and supplemental links upon said pins outside of corresponding first named links, the supplemental links having spaced laterally disposed apertured ears. 75

5. A chain link having holes near opposite ends and spaced ears extending laterally from opposite edges of said link between said holes, said ears having registering apertures. 80

Signed at Passaic, in the county of Passaic and State of New Jersey, this 29th day of November, A. D. 1921.

ISAAC W. ENGLAND.
